UNITED STATES PATENT OFFICE

VÄINÖ PIISPAHEN, OF HELSINKI, FINLAND, ASSIGNOR TO KOEHRING COMPANY, OF MILWAUKEE, WISCONSIN, A CORPORATION

CONCRETE MIXER

Application filed January 30, 1930, Serial No. 424,638, and in Finland May 22, 1929.

The present invention comprises a novel construction of mixing machine, primarily designed for the admixture of concrete, and involving new and peculiar means for supporting the mixing drum of the machine in order to facilitate the movement of said drum from a mixing position to a dumping position, and vice versa.

In carrying out the invention, the especial novel feature of the construction resides in mounting the mixing drum so that it rotates about a shaft, and is supported at one side of the drum only. The shaft which carries the drum is of peculiar bent formation, so as to enable the drum to have the necessary movement for assuming its mixing and dumping positions.

The construction of the present mixing machine is designed also for the utmost simplicity and cheapness of manufacture obtained by the employment of relatively few parts advantageously combined and arranged.

In the accompanying drawings:—

Figure 1 is a perspective view of one embodiment of the invention in practical form.

Figure 2 is a sectional view taken about on a horizontal plane through the drum and supporting standard.

Describing this invention specifically, and referring to the drawings, as to exemplification thereof, the numeral 1 denotes the mixing drum itself, the same arranged to rotate freely upon the shaft 2 by the provision of a central journal member 1^a in the form of a casting of somewhat bell shape which casting constitutes the central supported portion of the drum 1, combining with the body of the drum to provide a suitable receptacle for the concrete which receptacle or drum is open at one end only, somewhat after the manner of tilting or tumbler type mixers at present in use.

The shaft 2 is bent or of angular form, one end of arm of the shaft entering the journal portion 1^a of the drum and the other end being mounted for rotation in the bearing members 6 and 7 extending laterally from the upper horizontal arm 5 of a supporting standard 12 at the lower end of which is a supporting

base 13 of T-form. The shaft 2 may be rotated in the bearings 6 and 7 aforesaid, by means of a lever 8. When so rotated, the movement of the shaft 2 will shift the drum so that its open end raises or lowers, lowering in order to dump, and assuming a raised or uppermost position when it is desired to mix the aggregates or concrete materials. In this way, the drum may be quickly emptied or lifted to its mixing position.

For the rotation of the drum 1 in order to perform its mixing function, there is provided a bevel gear 3 rotatively mounted upon one end of the shaft 2 and meshing with bevel gear teeth of a gear ring 4 formed on the body of a drum and carried directly by the central casting at the end of the latter opposite the open end of the drum. Attached or formed with the bevel gear 3 is a handle extension 9^a carrying the crank handle 9 by which the gear 3 may be turned in order to impart rotation to the drum 1.

As a convenient means for locking the drum 1 in its mixing position, a latch member 14 is mounted on a side of the horizontal arm of the standard 12 and the nose of the latch member is adapted to engage over the lever or handle 8 by which the drum 1 is rocked for causing it to assume dumping or mixing positions. The handle 8 is carried by a collar 8^a pinned at 8^b to the shaft 2.

The body of the drum 1 is preferably of sheet metal riveted or otherwise secured to the central casting having the journal member 1^a. Moving the handle 8 rocks the drum in an obvious manner. The shaft 2 is provided with a stop ring 10 and a protecting hood 11 at the free end of the journal member 1^a. The drum is equipped interiorly with the usual mixing blades, not shown.

Having thus described my invention, what I claim as new and desire to secure by Letters Patent of the United States, is:—

1. A concrete mixing machine, comprising a drum open at one end, and closed at its other end, a support, an angular shaft rotatable upon the support and supported at one end by the support, means connecting the other end of the shaft with the mixing drum, and means for moving the shaft to turn the

drum from mixing to discharging position, together with means for rotating the drum relatively to the shaft.

2. A concrete mixing machine, comprising a mixing drum closed at one end and open 5 at its other end, a journal member at the closed end of the drum, a support, a shaft of angular form mounted at one end upon the support and having its other end cooperative with the journal member of the drum, means 10 carried by the drum for turning it with the shaft to shift the drum from mixing to dumping position and vice versa, means on the support geared to the drum for rotating the drum relatively to the shaft, and a lock 15 device cooperating to hold the drum in a predetermined position.

3. A tilting drum type concrete mixer, comprising a supporting standard, a drum mounting means carried by said standard including 20 a relatively horizontal portion having a drum supporting portion extending at an angle from the end thereof so that when the drum supporting portion extends at one angle relatively to the horizontal portion a drum carried thereby will assume a non-discharging position, whereas when the angularly extending drum supporting portion is turned 25 at another angle relatively to the horizontal portion and with said horizontal portion as an axis, the drum carried thereby will be in discharging position, a drum mounted upon 30 said drum supporting portion, and devices for turning the drum about the axis formed by the angularly extending drum supporting means and for turning the mounting 35 means about the axis provided by the horizontal portion thereof so as to cause non-discharging or discharging inclinations to be assumed by the drum.

4. A tilting drum type concrete mixer, comprising a supporting standard, a drum mounting means carried by said standard including a relatively horizontal portion having 40 a drum supporting portion extending at an angle from the end thereof so that when the drum supporting portion extends at one angle relatively to the horizontal portion a drum carried thereby will assume a non-discharging position, whereas when the angularly extending drum supporting portion is turned 45 at another angle relatively to the horizontal portion and with said horizontal portion as an axis, the drum carried thereby will be in discharging position, a drum mounted upon 50 said drum supporting portion, a gear carried by the drum and having the angularly extending portion of the mounting means coaxial therewith, and a gear carried 55 by the horizontal portion of the mounting means and meshing with the gear on the drum, together with means for turning the second mentioned gear for causing rotation 60 of the drum, and means for turning the horizontal portion of the mounting means for 65

causing non-discharging and discharging adjustments of the drum representing different inclinations thereof.

5. A tilting drum type concrete mixer comprising a supporting standard, drum mounting means carried by the standard and including a horizontal shaft portion to rotate on the standard and an angularly extending drum supporting portion projecting from an end of the said horizontal shaft portion, a drum mounted upon said angularly extending portion and free to rotate relatively thereto, a gear carried by the drum and coaxial with the angularly extending portion of said shaft means, a gear carried by the horizontal shaft portion and meshing with the gear on the drum, means for turning the last mentioned gear to thereby communicate turning movement to the gear on the drum, and the drum itself, and means for turning the angularly extending portion of the said horizontal shaft so as to change its inclination to opposite positions in one of which it will hold the drum for discharging action, and in the other of which it will hold the drum for non-discharging action.

6. A concrete mixer as set forth in claim 5, wherein the last mentioned means is a lever connected to rotate the drum with the horizontal shaft portion as the turning axis, and latch means associated with the drum turning means for normally holding the drum in a non-discharging upwardly inclined position.

In testimony whereof I affix my signature.
